UNITED STATES PATENT OFFICE.

EDDIE L. GRAY, OF TUPELO, MISSISSIPPI.

FOLDING POULTRY-CRATE.

1,252,341.

Specification of Letters Patent.

Patented Jan. 1, 1918.

Application filed March 29, 1916. Serial No. 87,566.

To all whom it may concern:

Be it known that I, EDDIE L. GRAY, a citizen of the United States, residing at Tupelo, in the county of Lee and State of 5 Mississippi, have invented new and useful Improvements in Folding Poultry-Crates, of which the following is a specification.

This invention relates to folding poultry crates and it consists in the novel features 10 hereinafter described and claimed.

An object of the invention is to provide a crate of the character indicated which may be conveniently and economically used for the purpose of shipping poultry to the 15 market and after the crate has been emptied of its contents it may be collapsed in compact form whereby it may be reshipped to the producer at small or nominal cost for transportation.

20 With the above object in view the crate comprises a bottom bound about its edges with upstanding flanges. Side and end panels are hingedly mounted upon the said flanges and are adapted to swing upon axes 25 located approximately above the median longitudinal dimensions of the said flanges. The end panels however are arranged to swing about the median longitudinal dimensions of the end flanges in order that 30 they may lie flat against the bottom when the crate is collapsed. The side panels are provided at their free edges and at one end with inwardly disposed lugs against which one of the end panels is adapted to bear 35 when the parts are in extended position. The said end panel is provided at its free edge with an upstanding lug and the opposite end panel is provided at its free edge with upstanding pins. The side panels are 40 provided in the vicinity of their hinged edges with pins, the pins at the hinged edge being located the same distance from each other as the pins at the free edges.

A top panel is provided and the same carries at its sides and in the vicinity of one end fixed hooks and at its opposite end portion and opposite sides pivotally mounted spring actuated hooks. The said top panel when the parts of the crate are extended is 50 adapted to rest upon the upper edges of the side and end panels and the fixed hooks engage the pins at one end of the side panels while the pivoted hooks engage the pins at the opposite ends thereof. The said top 55 panel is further provided at its side edge portions with pins adapted to engage in

sockets in the free edges of the side panels when the parts of the crate are in extended position.

In the accompanying drawing:

Figure 1 is a perspective view of the crate showing the parts in extended positions.

Fig. 2 is a vertical longitudinal sectional view of the same.

Fig. 3 is an end elevation of the same.

Fig. 4 is a transverse sectional view of the same.

Fig. 5 is a top plan view of the same.

Fig. 6 is a longitudinal sectional view of the same taken on the line 6—6 of Fig. 5, 70 and showing the parts collapsed.

Fig. 7 is a transverse sectional view of the same taken on the line 7—7 of Fig. 5 and showing the parts collapsed.

Fig. 8 is a fragmentary perspective view 75 of parts of the crate.

The crate includes a bottom member 1 which is bounded along its longitudinal edges by upstanding side flanges 2 and along its transverse edges with upstanding end 80 flanges 3. The end flanges 3 are chamfered or beveled at their upper inner edges.

The end panels 4 are hingedly connected with the end flanges 3 by means of clips 5 which are fixedly connected with the said 85 end panels and pass under and around the lower portions of the end flanges 3. The said clips serve as hinged members for connecting the end panels with the end flanges and the end panels may be swung down 90 upon the upper surface of the bottom member 1 when the parts of the crate are collapsed. One of the end panels 4 is provided at its free edge with an upstanding lug 6 and the other end panel 4 is provided at its 95 free edge and in the vicinity of its corners with upstanding pins 7.

Side panels 8 are hingedly mounted upon the side flanges 2 by means of clips 9 which are fixedly connected with the side 100 flanges and which receive the edge portions of the side panels 8 so that the said side panels may swing within the said clips. The lower inner edges of the side panels 8 are chamfered or beveled and the said side 105 panels may swing down over the end panels 4 after the said end panels have been swung down against the upper surface of the bottom 1. The side panels 8 are provided at their lower portions with pins 10 and at 110 their upper portions with pins 11. The axes of the pins 10 are disposed at a right

angle to the axes of the pins 11 so that the axes of the pins 10 are inwardly disposed when the side panels 8 are swung down and the axes of the pins 11 are inwardly disposed when the side panels 8 are swung up into vertical position with relation to the bottom 1.

The side panels 8 are provided in the vicinity of one end with inwardly disposed 10 lugs 12 and in the vicinity of their opposite ends with sockets 13.

A top panel 14 is provided in the vicinity of one end and approximately at its corners with fixed hooks 15. Pivoted hooks 16 are 15 located in the vicinity of the opposite corners of the top panel and springs 17 are connected at one end with the hook 16 and at their other end with the said top panel. The top panel 14 is provided in the vicinity 20 of its side edges and at its undersurface with pins 18 adapted to enter the sockets 13 in the side panels 8 when the parts of the crate are in erected position. The said pins 18 may also be inserted in sockets 19 when 25 the parts of the crate are collapsed or folded. The bottom member and the panels hereinbefore described may be provided with suitable braces and the side end and top panels are open at their intermediate portions and 30 the said openings are covered with open mesh wire whereby the crate may be used for shipping poultry and sufficient air may be admitted into the interior thereof for ventilation. The openings through the material applied to the side, top and end panels 35 also afford means for observing the interior of the crate.

When the parts of the crate are extended or set up the side panels 8 are in vertical 40 position above the side flanges 2 and the end panels 4 are in vertical positions above the end flanges 3. When so positioned the end panel 4 which carries the lug 6 is in engagement with the lugs 12 located at one end of 45 the side panels 8. One end of the top panel 14 is in engagement with the inner surface of the lug 6 and the fixed hooks 15 engage the upper pins 11 at one end of the side panels 8 and the pivoted hooks 16 engage the 50 pins 11 at the other end of the side panels 8 also the pins 7 upon one of the end panels 4 engage in sockets provided at the end of the top panel 14 and the pins 18 carried by the top panels engage in the sockets 13 at the 55 free edge portions of the side panels 8. Thus the parts are securely held in extended positions.

To collapse or fold the crate an operator swings the hooks 16 against the influence 60 of the spring 17 whereby the said hooks are

disengaged from the pins 11 and one end of the top panel 14 is moved in an upward direction whereby the fixed hooks 15 are disengaged from the other pins 11, thus the top panel may be removed from over the 65 upper edges of the side and end panels. The end panels 4 are then swung down into close contact with the upper surface of the bottom 1 and the side panels 8 are swung down over the end panels 4. The top panel 14 is 70 then placed in position over the upper surfaces of the side panels 8 and the pins 18 are inserted in the sockets 19 of the side panels. The fixed hooks 15 are engaged with the pins 10 upon the side panels at one end thereof and the pivoted hooks 16 are engaged with the pins 10 upon the side panels in the vicinity of the opposite ends thereof. Thus the parts are secured in collapsed or folded 75 position.

From the foregoing description taken in conjunction with the accompanying drawing it will be seen that a poultry crate of simple and durable structure is provided and that the same may be economically and 80 conveniently used for transportation and when it is desired to return or reship the same the parts may be folded into small compass thereby materially reducing the cost of handling and reshipment.

Having described the invention what is claimed is:—

A crate comprising a bottom member, sides and end panels hingedly connected therewith, means for connecting the free 95 edges of the end panels with the ends of the side panels, inwardly disposed upper pins carried by the side panels and located in the vicinity of the ends thereof, a top panel having at one end fixed hooks located within the 100 edges thereof and adapted to engage the upper pins upon the side panels in the vicinity of one end thereof, pivoted hooks mounted on the top panel at points within the edges thereof and in the vicinity of the 105 other end of the top panel and passing through the same and adapted to engage the other upper pins on the side panels, springs connected with said pivoted hooks and the top panel and other pins carried at the 110 lower end portions of the side panels and disposed at right angles to the upper pins and engageable by the hooks when the parts are collapsed.

In testimony whereof I affix my signature 115 in presence of two witnesses.

EDDIE L. GRAY.
